RUBBER BOOT FOR DOLLS

Emil Gottschalk, New York, N. Y.

Application April 12, 1950, Serial No. 9,155

Term of patent 14 years

(Cl. D7—4)

To all whom it may concern:

Be it known that I, Emil Gottschalk, a citizen of the United States, residing at 537 West 53rd Street, in the county of New York and the State of New York, have invented a new, original, and ornamental Design for a Rubber Boot for Dolls, of which the following is a specification, reference being had to the accompanying drawing, forming a part thereof.

My design for a rubber boot for dolls is characterized by the row of bright headed elements of ornamentation on either side of the zipper opening, in combination with the exact configuration, all as illustrated.

I claim:

The ornamental design for a rubber boot for dolls, substantially as shown and described.

EMIL GOTTSCHALK.
